DESIGN FOR A CHAIR

Willard H. Bond, Jr., East Grand Rapids, Mich.,
assignor to American Seating Company, Grand Rapids, Mich., a corporation of New Jersey

Application May 10, 1937, Serial No. 69,281

Term of patent 7 years

To whom it may concern:

Be it known that I, Willard H. Bond, Jr., a citizen of the United States, residing at East Grand Rapids, in the county of Kent and State of Michigan, have invented a new, original, and ornamental Design for a Chair, of which the following is a specification, reference being had to the accompanying drawing, forming a part thereof, in which:—

The figure is a perspective view of a chair showing my new design, the distinguishing, essential and dominant features or characteristics of the design being the end standards or panels forming the supporting legs and feet of the chair which are shown in full lines.

I claim:

The ornamental design for a chair as shown and described.
